METAL SHAVING TOOL

Arnaud P. Bidart, Jr., Los Angeles, Calif., assignor to Zephyr Manufacturing Co., Inglewood, Calif., a co-partnership

Application August 4, 1958, Serial No. 752,887

2 Claims. (Cl. 90—12)

This invention has to do generally with milling tools and relates more particularly to a hand-manipulated tool of the type generally referred to as a "shaver," being peculiarly adapted for machining or shaving off projections on work sheets. For instance, a field in which my tool finds considerable use is in the aircraft manufacturing industry, where it is used to shave rivet heads projecting from sheets so that they become flush with the surrounding sheet surface.

I am aware that tools of this general type are well known in the art, but those of which I am aware have possessed certain shortcomings in that it is difficult to initially, accurately position the tool over the projection to be shaved with proper evenness and flushness. Also, those prior tools of which I am aware, do not provide means for automatically retracting the cutting element when it is not being applied to work, which means are very important to avoid personal injuries to workers operating such tools. An additional shortcoming of prior tools of this character is that they do not have efficient means for readily and accurately adjusting the tool to a predetermined depth of cut so as to prevent cutting below the plane of the surface of the work sheet. Still another shortcoming of prior tools is that they tend to become clogged with metal cuttings produced by the cutting operation.

It is, therefore, among the objects of my invention to provide a tool of this character incorporating a resiliently mounted, easily adjustable, nose member or cutter guard, which enables the tool to be positioned in proper flush relation with or perpendicular to the sheet surface from which the projection being shaved extends; the adjustable nose piece functioning automatically to retract the cutter when not being used, as well as to limit the depth of the cut.

Another object is the means which I provide for utilizing the air exhausted from the air motor, conventionally used to operate such tools, for the purpose of constantly blowing out of the tool cuttings as they are produced by the cutter, and, in this connection, the novel nose piece of my tool is particularly constructed to facilitate the carrying out of this purpose.

While I shall point out in the appended claims the features and combinations which I consider to be new, I shall now, for the purpose of enabling those skilled in the art to make and use it, describe a presently preferred embodiment of my invention, for which purpose I shall refer to the accompanying drawing, wherein:

Fig. 1 is a side elevation;

Fig. 2 is an enlarged sectional view taken on line 2—2 of Fig. 3; and

Fig. 3 is a view taken on line 3—3 of Fig. 2.

Referring now to the drawing, I show a hand-manipulated tool of the "gun" type, comprising a body 5 in the upper part of which there is mounted a conventional air motor, not illustrated in the drawing because any conventional air motor will suffice for the purpose of my invention. The handle portion 5a of the body car-

2

ries a spring-loaded trigger plunger 6 for manipulating the valve (not shown) controlling the air line leading to the motor.

Threaded into the internally threaded bottom flange 5 portion 15 of the upper part of the body, there is a housing member 17 carrying ball bearings 19 (only one of which is shown) for journaling a drive shaft 20 driven by the air motor.

The lower end of the housing member 17 presents an annular cavity 22 in which a ring gear 24 is mounted, the ring gear being free to rotate in the cavity, but being secured, as by pins 25, to a cage 30 which is rotatably carried in a sleeve 32 threaded onto the housing member 17.

For rotatably actuating the cage 30, I provide the drive shaft 20 with a worm thread 35 engaging a worm gear 36, rotatably mounted on stub shaft 37 whose outer end portion is fitted in a radial hole 38 through the housing member 17. Gear 36 meshes with a gear 40 secured on a shaft 42 whose bottom end carries a gear 43 which meshes with and rotates the ring gear to impart rotation to the cage 30 about the axis of the body while the cutter, to be hereinafter described, is rotated about an axis normal to the latter axis, for stabilizing purposes. As will be seen in the drawing, the gears 36 and 37 and the worm threaded portion 35 are disposed in a recess 45 in the housing member 17.

The bottom end of the drive shaft 20 has secured to it a beveled gear 50 which meshes with and drives another beveled gear 51 fixed on a horizontal shaft 53 journaled in ball bearings 54 in the cage.

The left end of shaft 53 has secured on it a gear 57 which drives a pair of gears 58, 59, the latter gear being secured on a cutter shaft 60 journaled in ball bearings 61. A cutter wheel 65 is secured on shaft 60, there being spacer sleeves 66, 67 interposed between the ends of the cutter and the bearings.

A nose assembly, generally denoted 70, comprises an inner sleeve 72 axially slotted at 73. This sleeve is slidably mounted on the sleeve 32 and is yieldably urged downwardly or protractively by a coil spring 75. A nose piece 77 is threaded onto the inner sleeve 72 for purposes of adjustment axially relative thereto, the top end of the nose piece having upwardly projecting teeth 80.

A lock ring 82 is slidably mounted on the inner sleeve 72 and has an enlarged diameter bottom end portion 83 engaging over the top end portion of the nose piece. This lock ring has an annular row of depending teeth 84 which normally mesh with teeth 80 so that, when the teeth are engaged, the nose piece is retained by the lock ring against rotation. The lock ring is held against rotation by a set screw 87 threaded through a sleeve 85 frictionally fitted on sleeve 32, the screw extending through an axial slot 88 in the lock ring, as well as through the previously described slot 73 in the sleeve 72. The lock ring is yieldably urged downwardly against the outer end portion of the nose piece by a coil spring 90, which is relatively more stiff than the previously described spring 75.

The bottom end wall 91 of the nose piece has a central aperture 92 centered below the cutter 65. As will be noted from the drawing, the bottom end wall 91 of the nose piece is made in two parts, the inner part 91a being threaded into the surrounding part 91b.

As best shown in Fig. 2, the air exhausted from the air motor is passed downwardly through a port 95 which discharges into an annular channel 96 in the upper end of the cage, and from this channel the air is passed on downwardly through a port 97, discharging directly about the cutter 65.

Operation of the device is as follows: to adjust the nose piece to enable the cutter to cut to the desired depth, the

lock ring is first manually moved upwardly against the pressure of spring 90 to disengage the teeth 80, 84. Then the nose piece is manually rotated until the desired distance is provided between the peripheral or cutting surface of the cutter and the bottom plane of the wall 91a of the nose piece, after which the locking ring is released to reengage said teeth and thus lock the nose piece against further rotation relative to the inner sleeve. To facilitate meticulous adjustment, I provide adjustment scale indicia 98 around the periphery of the nose piece and a cooperating marker 99 on the lock ring.

To begin the shaving operation, the tool is manually placed over the projection to be shaved with the projection substantially centered in the aperture 92 beneath the cutter. In this position, the bottom wall of the nose piece around the aperture engages the surface of the sheet around the projection, while the cutter engages the projection. The operator then manually manipulates the trigger plunger 86 to actuate the air motor and thereby rotate the cutter. As the shaving operation proceeds to grind or shave away the projection, the nose piece will be gradually forced upwardly against the pressure of spring 75 until the sleeve 72 abuts the set screw 87, which limits the depth to which the cutting can go. In the course of this operation, the cage 30 with its carried parts is rotated about the axis of the body while the cutter rotates about an axis normal thereto, so that the tool is stabilized. The air exhausted from the air motor blows the cuttings out from about the cutter and through the openings 100, provided in the bottom end of the nose piece at and adjacent the periphery of the latter.

I claim:

1. A shaving tool for machining off that portion of a rivet or the like which projects outwardly beyond the surface of a riveted article, comprising a body including an upper portion having a sleeve portion depending there-

from and a cage portion mounted for rotation in and relative to said sleeve portion, a cutter wheel mounted in said cage portion for rotation about an axis normal to the axis of rotation of said cage portion, means for simultaneously rotating said cage portion and said cutter wheel about their respective axes, said cutter wheel having its cutting surface exposed at the bottom of said cage, a nose assembly carried by the bottom end portion of said sleeve, including an exteriorly threaded second sleeve slidably mounted on said first mentioned sleeve, resilient means yieldably urging said second sleeve downwardly of said first mentioned sleeve, a cup shaped nose piece having a side wall adjustably threaded on said second sleeve and a bottom end wall having an aperture normally underlying said cutting surface of said cutter wheel, and means for releasably locking said nose piece in adjusted position relative to and axially of said sleeve.

2. The tool of claim 1 wherein said means for releasably locking said nose piece in adjusted position relative to said second sleeve includes a locking sleeve slidably mounted on said second sleeve coaxial with and in normal end-to-end abutting relationship to said nose piece, and the contiguous end portions of said locking ring and said nose piece having normally interengaging teeth, spring means yieldably urging said teeth into interengagement, and means securing said locking sleeve against rotation relative to said nose piece.
